UNITED STATES PATENT OFFICE.

EUGENE C. CHANDLER, OF SYCAMORE, ILLINOIS, ASSIGNOR OF ONE-HALF TO WALTER E. HECHT, OF CHICAGO, ILLINOIS.

TROUSERS-CREASER.

SPECIFICATION forming part of Letters Patent No. 752,141, dated February 16, 1904.

Application filed November 14, 1901. Serial No. 82,272. (No model.)

To all whom it may concern:

Be it known that I, EUGENE C. CHANDLER, of Sycamore, Illinois, have invented certain new and useful Improvements in Trouser-creasers, of which the following is a specification.

This invention relates to improvements in trousers-creasers, and refers more specifically to a pressing device comprising a pair of co-
operating metal rollers mounted upon suitable handles arranged tong fashion and adapted to crease the garment by passing the folds there-between.

The object of the invention is to provide a simple handy device which may be used to crease the trousers without necessarily removing the garment from the wearer.

To this end the invention consists in the matters hereinafter described, and more particularly pointed out in the appended claims, and the same will be readily understood from the following description, reference being had to the accompanying drawings, in which—

Figure 1 is a plan view of a preferred embodiment of my invention. Fig. 2 is a side elevation of same, a fold of cloth or portion of a trousers-leg being shown in dotted lines as interposed between the pressing-rollers; and Fig. 3 is an end view looking at the rollers.

Referring to the drawings, 5 and 6 respectively designate a pair of tong-like arms which are preferably made of flat strap metal and pivoted together tong fashion at a point intermediate their lengths, as indicated at 7, said arms being outwardly bowed, so as to carry the handled ends of the arms well out of the plane of operation of the rollers. 8 and 9 designate the pair of rollers journaled upon the ends of the respective arms 5 and 6, so as to occupy the same plane, the axes or pivot-studs 10 and 11, upon which said rollers are journaled, being arranged parallel with each other and the meeting surfaces of the rollers being cylindric, so as to fit uniformly together throughout their faces or meeting portions. The supporting-studs 10 and 11 are desirably united rigidly with their respective arms in any suitable manner—as, for example, by screw-threaded connections or by riveting.

In order to aid in properly guiding the fold of cloth between the rollers, a guard is provided which serves to limit the extent to which the fold may be inserted between the rollers and also the extent to which the rollers may be separated, said guard being in the present instance formed in the shape of an arm 12, formed integrally with one of the main supporting-arms, as 5, and extending across the opposite arm in a curve concentric with the pivotal axis 7 of the device. To limit the extent to which the rollers may be separated, the outer end of the guard is slotted, as indicated at 13, and arranged to engage an extension of the pivot-stud 11 of the roller 9, said slot being curved concentrically with the pivot-axis of the device and being closed at both ends. Desirably and as shown herein the guard is deflected or offset between its ends, as indicated at 14, so as to overlie the end of the arm 6, while permitting its main body portion, which acts as a guard, to rest closely adjacent to the rear sides of the pressing-rollers.

As an important feature contributing to the convenience of use of the device I round the corners of the rolls, as indicated at 15, slightly, thereby greatly facilitating the adjustment of the rollers to pass upon the fold and avoiding forming a sharp line of demarcation between the pressed and unpressed portions of the garment. The ends of the arms 5 and 6 opposite the roller-supporting ends are provided with suitable handles, preferably of wood or other material not a good conductor of heat.

In using the device the rollers will preferably be heated by any suitable means—as, for example, a gas-jet or by placing them upon a suitable heating-stove—and then applied to the garment in the manner indicated in Fig. 2 and passed repeatedly along the fold until the latter has been creased to the desired extent. The operator by holding the fold partly in shape with one hand can pass the device up and down the leg of the trousers without removing the garment from the wearer and without any danger of burning or discommoding the wearer. The outward bowing of the arms enables the operator's hand which applies the

pressure to the rolls to be kept entirely out of contact with the garment, and the operation of creasing or recreeasing may be accomplished with the utmost expedition and convenience.

5 I claim as my invention—

1. A trousers-creaser comprising a pair of arms pivoted together intermediate their ends tong fashion, a pair of rollers with plain, cylindrical, parallel, engaging faces mounted upon the ends of said arms and projecting substantially at right angles therefrom, and a guard-arm projecting from the end of one of said arms to the other, adjacent the inner ends of said rollers, and having operative connection with said latter arm, for the purposes shown and described.
2. In a trousers-creaser the combination of the flat metal arms pivoted together between their ends tong fashion, and also bowed between their ends, the cylindric rolls journaled upon the ends of the respective arms upon parallel axes, said rolls being of substantially equal length and the guard upon one of said

arms arranged to overlap the end of the opposite arm, and provided with a slot engaging 25 the stud upon said opposite arm and formed concentric with the axis of bodily movement of the rolls, substantially as described.

3. In a trousers-creaser the combination of the flat metal arms pivoted together between 30 their ends tong fashion, and also bowed between their ends, the cylindric rolls journaled upon the ends of the respective arms upon parallel axes, said rolls being of substantially equal length and having their corners remote 35 from the arms rounded, and the guard upon one of said arms arranged to overlap the end of the opposite arm, and provided with the slot engaging the stud upon said opposite arm and formed concentric with the axis of 40 bodily movement of the rolls, substantially as described.

EUGENE C. CHANDLER.
